UNITED STATES PATENT OFFICE

HARRIS HYMAN, OF BROOKLYN, NEW YORK

DESIGN FOR A PLAQUE OR SIMILAR ARTICLE

Application filed August 7, 1931. Serial No. 40,796. Term of patent 7 years.

To all whom it may concern:

Be it known that I, HARRIS HYMAN, a citizen of the United States, residing at Brooklyn, in the county of Kings and State of New York, have invented a new, original, and ornamental Design for a Plaque or Similar Article, of which the following is a specification, reference being had to the accompanying drawings, forming part thereof, wherein—

Fig. 1 shows a face view of the plaque or similar article; and

Fig. 2 is a side view.

I claim:

The ornamental design for a plaque or similar article substantially as shown.

HARRIS HYMAN.
